[57] CLAIM

An ornamental design for a pair of cushions for eyeglass
earpieces, as shown and described.

DESCRIPTION

FIG. 1 is a perspective view of a pair of cushions for
eyeglass earpieces showing my new design, the broken line
showing of the eyeglass frame is for illustrative purposes
only and forms no part of the claimed design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The showing of one cushion only in FIGS. 2—7 is for ease
of illustration only.
